(57) **CLAIM**

I claim the ornamental design for a vegetable cleaning and peeling machine, as shown.

DESCRIPTION

FIG. 1 is a perspective view of a vegetable cleaning and peeling machine showing my new design;

FIG. 2 is a side elevational view thereof as seen from the righthand side of FIG. 1;

FIG. 3 is a side elevational view thereof as seen from the lefthand side of FIG. 1;

FIG. 4 is an end view thereof as seen from the lefthand end of FIG. 2;

FIG. 5 is an end view thereof as seen from the righthand end of FIG. 2; and,

FIG. 6 is a top view thereof.
